TELESCOPIC BATHTUB

John A. H. Siers, Jersey City, N. J.

Application January 9, 1945, Serial No. 572,010

8 Claims. (Cl. 4—175)

1

This invention relates to an improved telescopic bath tub and has for its general object and purpose to provide a tub of this type having certain novel features of construction and arrangement of parts which will enable the tub to be easily installed and operated to open and closed position with ease and facility and, in the latter position, simulates an article of furniture so that, if desired, it may be arranged in the bedroom or other location remote from the usual bathroom fixtures.

Another object of the invention is to provide a sectional telescopic bath tub the several sections of which are preferably molded from a suitable plastic material of a selected color and co-operatively assembled for substantially noiseless relative sliding movement.

A further object resides in the provision of simple, easily operable means for positively securing the tub sections in their extended positions against relative movement which will also operate to establish an effective water-tight seal between adjacent tub sections to prevent leakage during use of the tub.

An additional object of the invention is to provide means for limiting the extension of the tub sections relative to each other so that they cannot be accidentally disconnected.

The invention further comprehends an inexpensively constructed bath tub as above characterized which will be strong and durable and, when closed, provides a complete protection for the internal tub surfaces against dust accumulation and is of such dimensions that it may be attractively combined with a vanity table or other decorative article of furniture.

With the above and other subordinate objects in view the invention comprises the improved telescopic bath tub and the form, construction and arrangement of the several parts as will hereinafter be more fully described, illustrated in the accompanying drawings and subsequently incorporated in the subjoined claims.

In the drawings, wherein I have shown one simple and practical embodiment of the invention and in which similar reference characters designate corresponding parts throughout the several views:

Figure 1 is a perspective view, showing the tub closed and a vanity table associated therewith as a useful and decorative adjunct.

Figure 2 is a side elevation of the tub when extended in condition for use.

Figure 3 is a top plan view.

2

Figure 4 is a longitudinal section taken substantially on the line 4—4 of Figure 3.

Figure 5 is a transverse sectional view taken substantially on the line 5—5 of Figure 4.

5 Figure 6 is a detail fragmentary vertical section on an enlarged scale, showing the means for producing a water-tight seal between the extended tub sections.

Figure 6A is a horizontal sectional view taken substantially on the line A—A of Figure 6.

Figure 7 is a fragmentary plan view showing one of the stop dogs for limiting the extension of the tub sections.

15 Figure 8 is a sectional view taken substantially on the line 8—8 of Figure 7, and

Figure 9 is a sectional view taken substantially on the line 9—9 of Figure 8.

Referring in further detail to the drawings, the 20 illustrated example of my invention comprises the front tub section 10, a rear section 11, and two intermediate sections 12 and 13, respectively. Each of these tub sections is molded from plastic material and is of general semi-circular form in cross-section. The sections successively increase

25 in width from the front to the rear and the opposite side walls of each section are formed adjacent to their upper edges with outwardly projecting longitudinal ribs, which are preferably of V-shaped cross-sectional form, as shown at 14.

30 These ribs on the respective tub sections have close interfitting sliding engagement with each other, as clearly shown in Figure 9 of the drawings.

The rear tub section 11 has a rear end wall 15 35 and is partially enclosed within an ornamental hood 16 which may also be formed of plastic material and suitably secured within an opening in the building wall 17. Water supply pipes, provided with the usual valves, open through the tub

40 wall 15 and suitable means 19 directs the water from the pipes 18 downwardly against the face of the wall 15, within the tub section 11. The overflow pipe 20 is also connected with the wall 15 and a drain pipe 21, joined to the overflow pipe,

45 extends upwardly through the floor 22 and is connected to the bottom of the tub section 11.

The forward end of the front tub section 10 is also provided with an ornamental plastic hood

23. The vertical sides of this hood closely approach the floor 22 and upon the inner faces thereof the rubber-tired rollers 24 are mounted. Relatively narrow top walls 25 extend inwardly from each of said side walls and to the front wall of said hood spaced handle members 26 of suitable ornamental form are secured.

The top wall 27 of the hood 16 is recessed at its forward edge and in this recess one edge of a cover plate 28 is hingedly mounted, as at 29. To the lower face of this plate soap receptacles 30 are attached and a hand knob 31 is secured to the upper face thereof. When the several tub sections are telescoped together in the closed position, the hood walls 25 and 27 are in abutting contact and the cover plate 28 is disposed in the same plane therewith between the walls 25. The front edge of the plate 28 is curved, as at 32, and forms a continuation of the front wall of the hood 23, as shown in Figure 1. Thus, the tub, when not in use, is completely closed and has an entirely flush top surface.

As shown in Figures 6 and 6A means is provided for securing the tub sections against relative movement in the extended position and for also establishing a water-tight seal between adjacent tub sections to prevent water leakage. As herein shown, the forward end of each tub section 11, 12 and 13 is formed with an inwardly opening semi-circular bead 33, the open side of which is opposed to the free portion of a compressible packing strip 34 cemented or otherwise fixed along one of its edges to the wall of the tub section. At each end of the bead 33 a lug 35 is formed having a vertical guide sleeve 36 fixed therein. A flat flexible steel band 37 is housed within the bead 33 and is adapted to be contracted against the compressible packing strip 34 by the bolts 38 on the ends of the band extending through the sleeves 36 and having the wing nuts 39 threaded on their upper ends. By adjusting the nuts it will be evident that the packing strip 34 will be uniformly compressed throughout its length against the outer face of the wall of the contiguous telescoping tub section to provide an effective seal preventing the escape of water from the tub.

Relative movement of the slidably engaged tub sections to their extended positions is limited by the simple stop device shown in Figures 7, 8 and 9. As shown, the upstanding edges of the outer tub sections at each side thereof are provided with vertical slots 40 in which the stop dogs 41 are pivoted at one of their ends, as at 42. The upper portion of the ribs 14 on the inner tub section are provided adjacent their ends with vertical recesses 43, forming the stop shoulders 44 with which the free ends of said dogs are adapted to engage when said recesses register with the slots 40. In the inward telescoping movement of the tub sections the latch dogs are forced upwardly into the slots 40.

As shown in Figure 1, a toilet table 45 and a mirror 46 may be mounted upon the rear hood 16 so that the tub, when closed, will form an attractive article of furniture. The cover 28 provides a secondary table surface and completely closes the top of the closed tub to prevent the accumulation of dust therein. As shown in Figure 4, a non-slip pad 47 may be suitably attached to the base of the front tub section 10. The plastic tub sections may be produced in various colors to harmonize with the other appointments of the room.

From the foregoing description it will be apparent that the above enumerated objects of the invention are achieved in an organization of simple mechanical elements which is characterized by efficient and reliable operation and durable and inexpensive construction. The operation of extending the tub sections or telescoping them to closed position is practically noiseless. When ex-

tended, the nuts 39 may be easily and quickly adjusted to contract the bands 37 and lock the tub sections against relative movement and in water-tight connection with each other. In the illustrated embodiment of the invention I have shown four of the tub sections but it is apparent that a greater number of said sections may be employed or said sections made of increased length, if a longer tub is desired.

Accordingly, while I have herein disclosed one desirable construction, it is nevertheless to be understood that the essential features of the invention are susceptible of embodiment in various other structural forms. Therefore, I reserve the privilege of resorting to all such legitimate changes in the form, construction and relative arrangement of the several parts, as may fairly be considered to be within the spirit and scope of the appended claims.

I claim:

1. A telescopic bath tub comprising a plurality of tub sections of similar cross-sectional form relatively slidable to open and closed position, coacting means on adjacent sections preventing relative angular displacement thereof with respect to the path of sliding movement and manually adjustable means carried by certain of said tub sections for locking the adjacent slidably engaged sections in extended position and establishing water-tight joints therebetween.

2. The telescopic bath tub defined in claim 1 in which each of said certain tub sections has a hollow bead formed on its front end and having an open side opposed to the wall of an adjacent tub section, and said manually adjustable means includes a compressible sealing strip and a contractible flexible band within said bead in permanent contact with the sealing strip.

3. The telescopic bath tub defined in claim 1 in which the side walls of said tub sections are formed with slidably engaged ribs and the ribs on adjacent telescoping sections are provided with co-acting means limiting relative movement of said sections to their extended positions.

4. The telescopic bath tub defined in claim 1 in which the side walls of said tub sections are formed adjacent to their upper edges with interfitting longitudinally extending ribs of V-shaped form in cross-section, together with means below said ribs for establishing a water-tight seal between adjacent tub sections.

5. A telescopic bath tub comprising a plurality of tub sections of similar cross sectional form relatively slidable to open and closed position, the rear end section and each intermediate section having means at its forward end to establish a water tight seal between adjacent sections and lock said sections in extended relation, each of said means comprising a compressible sealing strip carried by the tub section in contact with the outer surface of an adjacent section, and a manually adjustable member directly engaged with said sealing strip and operable to uniformly compress the same against the wall of the adjacent tub section and lock said adjacent sections against relative sliding movement.

6. The telescopic bath tub as defined in claim 5, in which said manually adjustable member is a contractible metal band in permanent contact with the sealing strip throughout its length.

7. The telescopic bath tub defined in claim 5, in which said manually adjustable member is a flexible element contacting the sealing strip throughout its length, together with guides fixed to the tub section, rods movable through said

guides connected to opposite ends of said element, and manually operable means connected to said rods to move the latter through said guides and contract said flexible member against the sealing strip.

8. A telescopic bath tub comprising a plurality of telescopically slidable tub sections including a rear fixed section and a front end section, an ornamental hood inclosing the rear portion of said rear tub section, an ornamental hood inclosing the front portion of said front tub section, said hoods having top walls disposed in a common horizontal plane when the tub sections are telescoped to substantially complete the cover and conceal the said tub sections, said top wall of the hood on the front tub section having a recess therein, and a cover plate hinged to the top wall of the rear hood and carrying a soap receptacle

received in said recess when the cover plate is disposed in closed position substantially in the plane of said hood walls.

JOHN A. H. SIERS.
